UNITED STATES PATENT OFFICE.

HAWLEY C. WHITE AND ALVIN H. MALLISON, OF NORTH BENNINGTON, VERMONT, ASSIGNORS TO H. C. WHITE CO., OF NORTH BENNINGTON, VERMONT, A CORPORATION OF VERMONT.

PHOTOGRAPHIC-PRINT WASHER.

SPECIFICATION forming part of Letters Patent No. 737,983, dated September 1, 1903.

Application filed April 23, 1903. Serial No. 153,909. (No model.)

To all whom it may concern:

Be it known that we, HAWLEY C. WHITE and ALVIN H. MALLISON, citizens of the United States, residing at North Bennington, in the county of Bennington and State of Vermont, have invented an Improvement in Photographic-Print Washers, of which the following is a specification.

In the various steps required for the production of photographs difficulties are constantly experienced in the washing of photographic prints, for the reason that abundant water and constant agitation are required, and the prolonged handling of prints is not only attended with great labor and close application; but is damaging to the edges and often to the surfaces of the prints. In washing photographic prints in bulk and to accomplish thorough work it is both desirable and necessary that each print be exposed on both sides to a current of running or constantly-changing water until it is free from all objectionable chemicals, and it has heretofore been found almost impossible to prevent the prints from packing together or sticking to each other during the washing process for various reasons. Where agitation by artificial means has been resorted to to keep the prints separated, they have often been injured by being brought in contact with the surfaces of the agitators or with the hands of the attendant. If prints in bulk are subjected to the washing process in a tank through which a running current of water passes, they are quite likely to float to the outlet end of the tank, where they will pack together closely, so that only those exposed directly to the flow of the water will be cleansed. In other cases on account of the tendency of saturated paper to sink in water they will all sink to the bottom of the washer or be carried around to the position of least agitation of the water, where they will collect in a body, so that only the outer prints will be acted on by the current. One difficulty in the washing process has been that where the prints are washed in large quantities in one receptacle they do not come out uniformly cleansed, so that to secure absolute cleansing of the prints it becomes neces-

sary to wash the whole batch until the foulest print is clean, and in doing this some prints are subjected to saturation much longer than is necessary, which is detrimental, and much time is lost by the prolonged washing.

The object of our invention is to overcome these difficulties by a device adapted for automatic operation and through which a current of clear water is caused to flow in a direction opposite to the tendency of the prints *en masse* to descend, the action of which will be to cause a separation of the prints from one another, so that the individual prints may descend gradually by gravity through the rising water, whereby the washing-water can act upon the entire surfaces of each print as periodically isolated to obtain a maximum of efficiency in a minimum of time consumed, the said operation being repeated at each automatic action of the device. The overflow-water is utilized to effect this automatic action and effect the inversion of the receptacle repeatedly and progressively.

We provide a receptacle or box pivotally mounted and adapted to receive a half-rotation in first one direction and then in the other. Water enters at about the central part and overflows through a device provided in the uppermost end and flows into a bucket on one side, filling the same, overbalancing the box and giving such a momentum to the box that a half-revolution is imparted thereto. A stop and yielding devices are preferably and advantageously provided for arresting this movement and holding the box at the end of each half-rotation. The rising water buoys up the prints, yet permits them to separate and gradually fall by gravity to the bottom through the rising water. This is accomplished between the semirevoluble movements. Consequently when the box turns the prints are at the top and commence to fall with a slow gentle undulating motion, and these movements are continuously repeated while the prints are washing. As the washing-water preferably enters at about the center of the box, the flow is confined to the upper part of the receptacle, the impurities or chemical salts, &c., washed from

the prints passing away with the discharged water, thus leaving the water in the lower portion quiescent, but clear, before the descending prints enter it.

5 In the drawings we have represented at Figure 1 a perspective view of our improved photographic-print washer, parts of the tank or case being broken open for clearness. Fig. 2 is an elevation and partial section; Fig. 3, 10 a section at right angles to the position Fig. 2 and partial elevation, and Fig. 4 is a partial plan view.

The tank or inclosure *a* preferably surrounds the box containing the washing-water 15 and is advantageously provided on at least one side with a platform *a'*. In the drawings this tank has been shown without a bottom, because the same may be connected to any suitable spillway device for carrying away 20 the washing-water, and the same forms no part of our invention. The semirevolv^{el} box *b* is mounted upon trunnions *b'*, carried by suitable bearing-frames secured within the tank or inclosure. The opposite ends of 25 the box are preferably recessed and provided with check-valves *d d'*, one valve being at the upper end and the other at the lower end in each movement of the washer, the valves preferably working by gravity, so that the 30 lowermost one is closed and the uppermost one open. Opposite edges of the box on the same side are provided with buckets *e e'*, which preferably agree in length with the width of the side and are of an appreciable depth.

35 Water is introduced into the box at about the central part by the pipe *f*, and the same fills the interior of the box. In the side of the box between the buckets *e e'* we prefer to employ a sleeve *g* and removable screw-cap 40 *g'*, connecting therewith. Opposite ends of the box are provided with finger-rods *h h'* on the center line of the box, and pivoted to the platform *a* is a spring-controlled arm *i*. The free end of this arm projects beyond the edge 45 of the platform toward the box, and the opposite end is preferably provided with eyes to which are connected springs 2 3, the other ends of the springs being connected to eyes at distant parts of the platform *a'*, the office 50 of the springs being to normally hold the arm *i* directly across or at right angles to the line of the platform *a* and form a stop for the finger-rods *h h'*.

Pivoted to the surface of the platform *a'* 5 and at opposite sides of the arm *i* are spring-controlled levers *k k'*. These levers are pivoted at 4. Their movement in one direction is stopped by pins 5, and their free ends come beneath the free end of the arm *i*. Springs 6 are interposed between parts of these levers and the bracket-blocks 7, secured to the surface of the platform, said levers being adapted to yield against the action of the springs 6 by the finger-rods *h h'* as they pass 65 by and move said levers with the opposite movements of the box.

We do not limit ourselves to the hereinbe-

fore-described devices for arresting the opposite movements of the box *b*, nor do we limit ourselves to the employment of any devices for the performance of this operation. 70

The prints to be washed are inserted in the box *b* through the sleeve *g* upon the removal of the screw-cap *g'* when the box is in a horizontal or substantially horizontal position, 75 with the screw-cap uppermost. In the position shown in Figs. 1 and 3, with the prints in the box to be washed, with sufficient water therein to float the prints, a flow of water is started through the pipe *f* into the box, and 80 the same fills up the box. The weight and position of the prints, even with the rising water, are sufficient to cause them to sink by gravity to the bottom of the box. Fig. 3 shows the valve *d* open and the valve *d'* 85 closed. Consequently the rising water passes out of the valve *d*, fills the recessed upper end of the box, flows over the lowered edge or spillway to the box into the bucket *e*. As soon as the bucket *e* is full the weight at this 90 side is sufficient to overbalance the box *b* and to cause the finger-rod *h* to pass by the lever *k*, and the weight of overbalancing causes sufficient momentum to impart to the box a half-rotation, which brings the check-valve 95 *d'* and the bucket *e'* uppermost, and the finger-rod *h'* in this movement passes by the yielding lever *k'* and stops against the surface of the spring-controlled arm *i*. This arm *i* yields to the force of the rotation as 100 delivered against it by the finger-rod *h'* and returns to a normal position, said finger-rod being retained between the free end of the arm *i* and the inclined surface of the lever *k'*. With this turning movement the prints 105 being washed within the box are brought to the top, and the individual prints at once commence to separate from the mass and descend through the box again by gravity with a slow, gentle, and undulating movement and the water to flow around and over all surfaces of the prints and out of the now open check-valve *d'*, the lowermost valve *d* being closed. Also in this movement the water from the bucket *e* and from the recessed 110 top of the box has spilled out within the tank and been conveyed away. The water now flows out of the check-valve *d'*, filling the recessed top of the box, overflows into the bucket *e'*, and when the bucket is full over- 115 balances the box, imparting a half-rotation to the same in a direction opposite to that of the first movement, in this movement spilling the water into the tank and bringing the valve *d* and bucket *e* uppermost and the 120 finger-rod *h* again into the position shown in Fig. 1. These movements are continuously repeated, a half-revolution being effected in first one direction and then in the other, the prints in each case within the box being at 125 the upper portion and falling by gravity through the rising water in the manner described to the bottom and in this way are 130 thoroughly washed without being handled or

injured, and we provide in the side of the box opposite to the sleeve *g* and screw-cap *g'* a plate of glass *8*, through which, if desired, the action of the washing-water and the movements of the prints may be viewed.

In the half-rotation of the box in first one direction and then in the other the finger-rods *h h'* strike against the curved edges of the levers *k k'*, causing the same to yield against the action of the springs *6*, so as to allow the finger-rods to pass by the levers. This partially arrests the momentum of the box, and when the finger-rods strike against the opposite surfaces of the spring-controlled arm *i* the movement of the box is arrested and the levers returned to their normal position of rest in Fig. 4, where said finger-rods are held, and further movement is prevented in the angle produced by the curved surfaces of said levers and the faces of said arm *i*, a notch, as it were, being thus produced for holding the finger-rods so as to retain the box in position and insure no movement of the box until the buckets are completely filled and ready to overflow, at which movement there is sufficient weight of water to cause either of the levers *k k'* to yield and permit either arm to pass by and the box to overturn and the respective movements to be repeated.

30 We claim as our invention—

1. In a photographic-print washer, the combination with a pivotally-mounted overbalancing box adapted to contain washing-water, of automatic devices at the respective ends of the box providing for the escape of the water at the uppermost end, and devices providing for the entrance of the washing-water at a point appreciably below the discharge, whereby an upward circulation of the washing-water is at all times maintained.

2. In a photographic-print washer, the combination with a pivotally-mounted box, of means for supplying water to the box and overflow devices acting in connection therewith for providing a rising circulation of the water, devices receiving the overflow-water for overbalancing the box and for causing a half-rotation thereto first in one direction and then in the other.

50 3. In a photographic-print washer, the combination with a pivotally-mounted box, of means for supplying water to the box, and overflow devices acting in connection therewith for providing a rising circulation of the water, devices receiving the overflow-water for overbalancing the box and for causing a half-rotation thereto first in one direction and then in the other, and yielding devices for arresting the box at the ends of the respective movements.

4. In a photographic-print washer, the combination with a tank or inclosure, of a pivotally-mounted box, means for supplying water to the box and overflow devices acting in connection therewith for providing a rising circulation of the water, devices receiving the overflow-water for overbalancing the box

and for causing a half-rotation thereto first in one direction and then in the other, and yielding devices for arresting the box at the ends of the respective movements.

5. In a photographic-print washer, the combination with a pivotally-mounted box, of means for supplying water to the box and overflow devices acting in connection therewith for providing a rising circulation of the water, devices receiving the overflow-water for overbalancing the box and for causing a half-rotation thereto first in one direction and then in the other, and means acting at the ends of the respective movements of the box for bringing the same to a state of rest.

6. In a photographic-print washer, the combination with a tank or inclosure, of a pivotally-mounted box, means for supplying water to the box and overflow devices acting in connection therewith for providing a rising circulation of the water, devices receiving the overflow-water for overbalancing the box and for causing a half-rotation thereto first in one direction and then in the other, and spring-controlled yielding devices, and devices on the box contacting therewith at the ends of the respective movements of the box for both arresting the movements of the box and for retaining the same in its respective positions.

7. In a photographic-print washer, the combination with a semirevolvable box, of trunnions and bearings for pivotally mounting the same in said tank or inclosure, check-valves in opposite recessed ends of the box, buckets at opposite ends of the box and upon the same side adapted to receive water overflowing from the recessed ends, a device in one side of the box through which the photographic prints to be washed are introduced, and means for supplying water to the box.

8. In a photographic-print washer, the combination with a tank or inclosure, of a semirevolvable box, trunnions and bearings for pivotally mounting the same in said tank or inclosure, check-valves in opposite recessed ends of the box, buckets at opposite ends of the box and upon the same side adapted to receive water overflowing from the recessed ends, a device in one side of the box through which the photographic prints to be washed are introduced, and means for supplying water to the box.

9. In a photographic-print washer, the combination with a tank or inclosure, of a semirevolvable box, trunnions and bearings for pivotally mounting the same, check-valves in opposite recessed ends of the box, buckets at opposite ends of the box and upon the same side adapted to receive water overflowing from the recessed ends, a device in one side of the box through which the photographic prints to be washed are introduced, means for supplying water to the box, means upon one side of the box and projecting beyond the respective recessed ends, and yielding devices mounted upon a part of the tank or inclosure

and with which the devices at the ends of the box contact so as to arrest the movement of the box and hold the same in its respective positions.

- 5 10. In a photographic-print washer, the combination with a tank or inclosure, of a semi-revolvle box, trunnions and bearings for pivotally mounting the same, check-valves in opposite recessed ends of the box, buckets at 10 opposite ends of the box and upon the same side adapted to receive water overflowing from the recessed ends, a device in one side of the box through which the photographic prints to be washed are introduced, means 15 for supplying water to the box, finger-rods secured to one side of the box and projecting beyond the recessed ends, a spring-controlled arm and spring-controlled levers mounted upon the platform of the tank or inclosure 20 and adapted for contact with the finger-rods at the ends of the respective movements of the box so as to stop the movements of the box and hold the same in its respective positions.
- 25 11. In a photographic-print washer, the combination with a tank or inclosure, of a semi-revolvle box, trunnions and bearings for pivotally mounting the same, check-valves in opposite recessed ends of the box, buckets at 30 opposite ends of the box and upon the same side adapted to receive water overflowing from the recessed ends, a device in one side of the box through which the photographic prints to be washed are introduced, means 35 for supplying water to the box, finger-rods *h h'* secured to one side of the box and projecting beyond the recessed ends, a pivoted spring-controlled lever *i* placed at right an-

gles to one side of the tank or inclosure and mounted upon the upper surface or platform 4 thereof and with which said finger-rods contact at the ends of the respective movements of the box, and levers *k k'* pivoted to the said platform provided with stops and springs for actuating the same and having curved surfaces, said levers being engaged by said finger-rods in their movements and pressed aside, and said finger-rods being held by the angle produced between the surfaces of said levers and the said spring-controlled arm, 5 substantially as set forth.

12. In a photographic-print washer, the combination with a tank or inclosure and a platform at the upper edge thereof, of a box, trunnions upon opposite sides of the box, 5 bearing-frames within the tank or inclosure pivotally supporting said box and opposite ends of the box being recessed, check-valves *d d'* in said recessed ends, buckets *e e'* upon the same side of the box and adjacent to the 6 opposite recessed ends to receive the overflow-water from said valves and recessed ends, a means for introducing the prints to be washed into the box, finger-rods *h h'* upon one side and projecting beyond said recessed 65 ends, a pivoted spring-controlled arm *i* and pivoted spring-actuated levers *k k'* engaging the said finger-rods, and a pipe *f* for supplying washing-water, substantially as and for the purposes set forth.

Signed by us this 23d day of February, 1903.
